UNITED STATES PATENT OFFICE.

WILLIAM M. BAXTER, OF CHICAGO, ILLINOIS, ASSIGNOR TO MILTON W. ARROWOOD,
OF CHICAGO, ILLINOIS.

METHOD AND MEANS FOR FEEDING POWDERED FUEL.

1,355,444.

Specification of Letters Patent. Patented Oct. 12, 1920.

Application filed April 27, 1918, Serial No. 231,070. Renewed December 24, 1919. Serial No. 347,200.

To all whom it may concern:

Be it known that I, WILLIAM M. BAXTER, a citizen of the United States, residing at Chicago, in the county of Cook and State 5 of Illinois, have invented certain new and useful Improvements in Methods and Means for Feeding Powdered Fuel, of which the following is a specification.

This invention relates in general to 10 method and means for feeding powdered fuel, and has more particular reference to the feeding of powdered coal and the thoroughly mixing therewith of the requisite amount of air so as to promote the high- 15 est combustive efficiency.

I am aware that prior to my invention various methods and apparatus have been employed with a view of mixing air and powdered coal, but in many of these systems now in use a considerable proportion 20 of the air employed for maintaining combustion is delivered directly to the combustion chamber instead of being supplied by the feeding apparatus. In other words, the 25 fuel when delivered to the combustion chamber is only partially mixed with air, and the particles of fuel, therefore, are not sufficiently separated one from another with the result that the imperfect mixture fed to the 30 combustion chamber does not burn evenly or instantaneously. Constant attention to such furnaces is required in order to maintain even an approximately efficient operation, and the slag compounds resulting 35 from comparatively low and uneven temperatures in the combustion chamber are deposited throughout the chamber, and in the case of a boiler, for instance, are even carried over into the tubes with very serious 40 results for the reason that the low oxids resulting from low combustion temperatures are when hot exceeding stiff, plastic and tenacious, and when cold, extremely hard and difficult to remove. The high oxids, on 45 the other hand, resulting from high combustion temperatures, such as I secure by perfect mixing and instantaneous combustion, are very fluid and flow freely when hot, and are very brittle and frangible when 50 cooled, so that in either condition these oxids are readily removable from the furnace.

One of the primary objects of my present

invention is the provision of a method and apparatus by which the powdered fuel is 55 thoroughly diffused and commingled with the requisite amount of air to properly and completely support combustion. In other words, my invention is designed to thoroughly separate the various particles of 60 fuel, and deliver each particle to the combustion chamber substantially equi-distant from every other particle, and immediately surrounded by the proper amount of air for its combustion. 65

Another object of the invention is to deliver all of the air to the combustion chamber along with the fuel so that it will not only thoroughly separate and diffuse the 70 fuel particles throughout the air, but by this method the air may be accurately controlled, and the proportions of air and fuel so regulated that highest efficiency in the combustion chamber will result, and when once the apparatus has been set it will 75 require no further attention so long as the character or quality of the fuel is uniform.

In some types of furnaces it is desirable to deliver to the combustion chamber a 80 regulated quantity of highly heated air, in addition to the relatively cool or partially heated air delivered with the fuel. Another object of my invention is to so deliver the mixture of fuel and air to the combustion 85 chamber that upon coming in contact with the highly heated air, the mixture of fuel and air will be immediately expanded, thus further separating and diffusing, by expansion, the fuel particles through the 90 heated air so as to promote instantaneous and perfect combustion without the necessity of employing a commingling jet or jets in conjunction with deflecting bridge walls and the like which has heretofore been considered necessary. 95

Instead of relying upon the subjection of the outside of a stream of fuel to the action of air currents as has heretofore been done for the purpose of commingling the air and fuel, I propose to deliver the air radially outwardly into a stream of fuel, and to produce cross currents and eddies of air in the fuel stream which will insure a thorough commingling of the air and fuel, and result in the fuel being carried in minute, 100 105 thoroughly separated particles, each sur-

rounded by sufficient air to insure its combustion in the combustion chamber.

For the purpose of facilitating an understanding of my invention, I have illustrated in the accompanying drawings one practical and preferred apparatus by which my improved method may be carried out.

Referring to the drawings:—

Figure 1 is a vertical sectional view 10 through an apparatus adapted to carry out my improved method;

Fig. 2 is an end view looking at the left-hand end of the apparatus shown in Fig. 1;

Fig. 3 is an end view of the delivery 15 nozzle and mixing chamber; and

Fig. 4 is a sectional view on the line 4—4 of Fig. 1.

In the drawings reference character 5 indicates a coal chute or hopper in which the 20 powdered fuel is stored, and from which it feeds downwardly to a screw conveyer 6 rotatably mounted in suitable bearings and adapted to operate in a cylindrical housing 7. This conveyer, as will be noted, comprises a shaft 8 provided with a worm and 25 is driven from a motor 9 through a shaft 11 which is equipped with a worm adapted to mesh with and drive a worm wheel mounted upon the shaft 8, the worm and worm 30 wheel being disposed within the housing 12.

As the powdered fuel is fed to the left, viewing Fig. 1, by the screw conveyer it is first subjected to a stream of air which is admitted into the housing 7 through a pipe 35 13. A fan blower (not shown) of any preferred construction is attached to the pipe 13 and serves to deliver the stream of air to the fuel under the requisite pressure. The air and fuel together continue to travel to 40 the left, viewing Fig. 1, into a horizontally disposed cylindrical member 14 having its open end arranged in the path of travel of the air and fuel. This member is provided with circumferential apertures 15 through 45 which the air and fuel are delivered radially outwardly in a direction at right angles to the original direction of travel of the fuel and air. This change in direction of the fuel and air, together with its division into 50 small streams passing outwardly through the apertures in the member serve to commingle the air and fuel to a considerable extent, and this commingling is further augmented by rotation of the member 14. The 55 member is mounted, as will be observed from Fig. 1, upon the shaft 8 and rotates therewith so that any chunks or lumps of fuel are shaken about and broken up until sufficiently pulverized to pass through the 60 apertures 15 in the walls of the member. The apparatus thus far described is known as the "coal control," and by varying the speed of the screw conveyer the amount of fuel fed to the furnace may be regulated. 65 In some instances the screen member 14

may be stationarily mounted instead of rotatably mounted upon the shaft. The air admitted through the pipe 13 is usually about one-half the amount required in the combustion chamber, and the purpose of 70 this part of the apparatus is to regulate the amount of coal and to diffuse the coal as thoroughly as possible throughout the air admitted at this stage.

After passing through the screen member 75 14 the stream of air and fuel flows downwardly through the passageway 16 into a burner or mixer indicated generally by reference character 17. This mixer is cylindrical in form and consists of a plurality 80 in the present instance four concentrically arranged cylinders numbered 18, 19, 21 and 22, respectively. These four cylinders provide four conduits or passages 23, 24, 25 and 26, respectively but obviously the number of cylinders and resultant passages may be increased or diminished according to the requirements of any particular installations. The conduits 23 and 25 are the fuel passages 85 through which the fuel and air from the screen member 15 pass from one end of the mixer to the other, and communication is established at the left end of the mixer between the passages 23 and 25 through a series of small pipes 27 shown in Figs. 1 and 90 4. The passages 26 and 24 are air passages and communication is established between these two passages around the pipes 27, as will be evident from Fig. 1. Air under pressure is supplied to the conduits 24 95 and 26 from a fan blower or air compressor 100 of any preferred type, preferably the same one to which the pipe 13 is connected, connected by means of suitable piping to the coupling 28 at the left-hand end of the mixer. 105 The right-hand ends of the conduits 25 and 23 are open except for supporting webs or brackets 29 which support the right-hand 110 ends of the cylinder, while the right-hand end of the chamber 24 is closed by a ring or flange 31.

The fuel and air from the screen member 15 are delivered through the passageway 16 to the left-hand end of the mixer where the stream is divided and flows in 115 two hollow cylindrical streams through the conduits 23 and 25, respectively. Air under pressure admitted at the left-hand end of the mixer through the coupling member 28 flows into the conduits 26 and 24. The 120 conduit 26 is provided with a series of circumferentially arranged perforations 32 disposed in staggered relation with respect to each other, and the air flowing under pressure in the conduit 26 is discharged outwardly through these apertures transversely of the conduit 25. The air escapes through these apertures in the form of radially disposed jets which are projected across the 125 path of travel of the air and fuel flowing 130

through the conduit 25, and as these jets impinge against the outer walls of the conduit 25, that is, against the inner faces of the cylinder 21, the jets are deflected and diffused, thereby setting up cross currents 5 and eddies which serve to further and thoroughly separate the fuel particles and to uniformly commingle them with the air.

The outer walls of the chamber 24 are 10 likewise provided with jet apertures 33, through which jets of air are projected radially outwardly into the conduit 23, and these jets projected across the path of travel of the flowing stream of fuel and air, and 15 deflected and diffused as they contact the outer walls of the chamber 23, separate and thoroughly commingle the fuel particles with the air so that a uniform mixture of the fuel with air is secured. Furthermore, 20 since the aggregate cross sectional area of the fuel passages 23 and 25 is greater than that of the passage 16, the fuel in these annular passages is under a reduced pressure. As a result of this reduction in pressure the 25 fuel streams in these passages are rarified or expanded and when the air jets which are under higher pressure as the result of the proportions of the passages through which the air is conducted, are projected into these 30 rarefied fuel streams the jets rapidly expand or open up within the fuel passages, thereby establishing the most favorable condition for the commingling of the air with the fuel, which commingling is then completely 35 accomplished not only by the direct action of the jets, but also by the eddies and cross-currents set up in these passages from the rebound of the jets and the cross firing of the currents.

40 Furthermore, the hollow traveling stream of fuel and air is more rare toward its periphery than toward the center and the radially issuing jets of air therefore encounter progressively less resistance as they penetrate through the stream. This fact results 45 in an increased expansion of the jets beyond the normal expansion which takes place in accordance with the laws governing the expansion of fluid streams issuing from restricted orifices, which causes a progressive 50 commingling of the air and fuel in the apparatus and thus facilitates the complete commingling.

The two hollow streams of fuel and air 55 issuing from the right-hand ends of the conduits 23 and 25 enter a tapering head or end member 34 which is gradually reduced in cross-sectional area and is connected at its extremity with the discharge nozzle 35 which discharges directly into the combustion chamber 36. This discharge nozzle, as will be evident from Fig. 3, is flat 60 and quite wide in proportion to its height so that the issuing stream of thoroughly 65 commingled fuel and air is discharged into

the combustion chamber in a substantially flat stream which presents a maximum surface area and readily diffuses throughout the combustion chamber and burns with high efficiency.

70

The right-hand end of the inner air cylinder 22 is also tapered and terminates in a discharge orifice or nozzle 37 which directs a jet of air into the outflowing stream of air and fuel in a direction longitudinally 75 of the stream and toward the discharge nozzle, thus further diffusing and mixing the fuel with the air. This mixing is facilitated also by the shape of the tapered head member 34 which is designed to set up cross 80 currents and eddies which are conducive to a thorough mixing of the air with the fuel.

It will be manifest from the foregoing that by causing the air and fuel to travel in certain defined directions, and by projecting radially outwardly into the streams of air and fuel jets of air under pressure which set up cross currents and eddies, I am enabled to supply to the combustion chamber all of the air necessary to support combustion of the fuel at the requisite temperatures, and am enabled to deliver the fuel in finely divided condition, each particle separated from the other particles and surrounded by the requisite amount of air for its 90 combustion. Since the quantity of air and the quantity of fuel can be varied and regulated to a fine degree of nicety, a proper mixture can be readily secured and accurately maintained, and this mixture is such that instantaneous combustion is produced in the combustion chamber, which causes the ash to be separated into highly-fluid slag and impalpable infusible powder. Furthermore the 95 instantaneous combustion resulting from the perfect mixture immediately burns any sulfur which may remain in the fuel with the result that the process is applicable in metallurgical work for the use of low grade sulfur coals which have not been available 100 heretofore with the older firing methods.

105 It is believed that my improved method and one practical apparatus for carrying the same into effect will be readily understood from the foregoing without further 110 description, but it should be obvious that the method, and also the apparatus for carrying it into effect, are capable of considerable modification without departing from the essence of the invention as set forth in 115 the following claims:—

I claim:

1. The method of feeding powdered fuel 120 which consists in subjecting a mass of fuel to a stream of air under pressure, dividing the resultant stream of fuel and air into a plurality of streams directed radially outwardly from the direction of travel of the original resultant stream, collecting said 125 plurality of streams into a cylindrically 130

formed stream, and delivering radially outwardly into said cylindrical stream a plurality of jets of air under pressure.

2. The method of feeding powdered fuel which consists in subjecting a mass of fuel to a stream of air under pressure, causing the resultant stream of fuel and air to assume a cylindrical shape, delivering radially outwardly into said cylindrical stream 10 a plurality of jets of air under pressure, converting said cylindrical stream into a solid stream of reduced cross-sectional area, and projecting a jet of air into said solid stream longitudinally thereof.
- 15 3. The method of feeding powdered fuel which consists in subjecting a mass of fuel to a stream of air under pressure, causing the resultant stream of fuel and air to assume a cylindrical shape, delivering radially outwardly into said cylindrical stream 20 a plurality of jets of air under pressure, converting said cylindrical stream into a solid stream of less cross-sectional area, and delivering said stream under pressure to a 25 point of combustion.

4. The method of feeding powdered fuel which consists in subjecting a mass of fuel to a stream of air under pressure, collecting the mixture of fuel and air into a hollow 30 tubular stream, delivering radially outwardly into said tubular stream a plurality of jets of air under pressure, reducing said tubular stream into a solid stream and delivering the same under pressure to a point 35 of combustion.

5. In an apparatus of the character described, the combination of an air conduit provided with a series of circumferential apertures, a fuel conduit surrounding said 40 air conduit and open at the ends thereof for the passage of fuel therethrough, a second air conduit surrounding said fuel conduit and communicating with said first-mentioned air conduit, said second air conduit 45 being provided with circumferential perforations, and a second fuel conduit surrounding said second air conduit and communicating with said first-mentioned fuel conduit.

50 6. In an apparatus of the character described, the combination of a series of concentrically disposed air and fuel conduits, the inner and alternate conduits being communicating air conduits, and the outer and 55 alternate conduits being communicating fuel conduits, means for supplying fuel to said fuel conduits, means for supplying air under pressure to said air conduits, and means whereby air is projected radially outwardly in jets from said air conduits into 60 said fuel conduits.

7. In an apparatus of the character described, the combination of an air conduit provided with a series of circumferential radially disposed apertures, a cylindrical fuel 65

conduit surrounding said air conduit with its surrounding walls in relatively close proximity to the walls of said air conduit, said fuel conduit being open at each end for the passage of fuel therethrough, means 70 for delivering a mixture of air and fuel under pressure to said fuel conduit, means for delivering air under pressure to said air conduit, said air being delivered in radial jets from said air conduit into said fuel 75 conduit, and means for delivering the resultant mixture delivered from said fuel conduit to a combustion chamber.

8. In an apparatus of the character described, the combination of concentrically 80 disposed air and fuel conduits, means for delivering air and fuel under pressure to said conduits respectively, said air conduit being provided with radially disposed apertures through which air is delivered therefrom in radial jets into said fuel conduit and against the surrounding walls thereof, and means for collecting into a solid stream 85 the mixture of air and fuel from said fuel conduit and delivering said stream to a combustion chamber.

9. In an apparatus of the character described, the combination of a cylindrical fuel conduit, a cylindrical air conduit disposed concentrically within said fuel conduit 95 said air conduit being provided with radially disposed apertures through which jets of air are projected radially outwardly into said fuel conduit, means for delivering air and fuel under pressure to said respective conduits, and means for delivering the resultant mixture from said fuel conduit to a point of combustion.

10. In an apparatus of the character described, the combination of means for supplying a quantity of powdered fuel, means for delivering a stream of air thereto, a cylindrical member disposed in the path of travel of said air and fuel and provided with circumferential perforations through 105 which the air and fuel are discharged from said member, and means for rotating said member.

11. In an apparatus of the character described, the combination of a cylindrical member open at one end and provided with circumferential perforations, means for delivering powdered fuel and air under pressure into the open end of said member, said fuel and air being discharged from the 115 member through said perforations in a radial direction, a cylindrical conduit for receiving said fuel and air, an air conduit arranged in said cylindrical conduit and provided with circumferential perforations 120 through which jets of air under pressure are delivered radially outwardly from said air conduit into the fuel conduit, and a delivery nozzle of reduced cross-sectional area connected with said fuel conduit through which 125 130

the commingled air and fuel are delivered into a combustion chamber.

12. In an apparatus of the character described, the combination of means for preliminarily mixing a quantity of powdered fuel with air under pressure, a cylindrical conduit through which said air and fuel are delivered under pressure, a stationary air conduit arranged within said cylindrical conduit and provided with circumferential perforations adapted to deliver jets of air under pressure radially outwardly into the fuel conduit, a discharge nozzle of reduced cross-sectional area connected with said fuel conduit, and means for delivering a jet of air into said fuel conduit in a longitudinal direction toward said nozzle.
13. The method of feeding powdered fuel which consists in preliminarily mixing a quantity of air with powdered fuel, converting the resultant stream of fuel and air into a hollow cylindrical stream of increased cross sectional area, and causing a plurality of jets of air under pressure to penetrate said hollow stream from the inside thereof and expand within said stream.
14. The method of feeding powdered fuel which consists in preliminarily mixing air with powdered fuel, converting the resultant stream of fuel and air into a rarefied hollow cylindrical stream, and so project-

ing a plurality of jets of air under pressure into said rarefied stream that the expansion of said jets will cause the fuel to be commingled with air.

35

15. The method of feeding powdered fuel which consists in preliminarily mixing air with powdered fuel, converting the resultant stream of fuel and air into a hollow cylindrical stream, and causing jets of air under pressure to pass transversely through said stream and be deflected back into said stream to further commingle said fuel with air.

40

16. The method of feeding powdered fuel which consists in preliminarily mixing air with powdered fuel, converting the resultant stream of fuel and air into a rarefied cylindrical stream, projecting jets of air under pressure radially into said stream and causing said jets to expand and be deflected into said stream.

45

17. The method of feeding powdered fuel which consists in preliminarily mixing air with powdered fuel, converting the resultant stream of fuel and air into a hollow cylindrical stream and projecting jets of air under pressure radially into said stream, so as to cause a progressive commingling between said jets and said stream.
